UNITED STATES PATENT OFFICE.

DOROTHY R. WATERS, OF NEW YORK, N. Y., ASSIGNOR TO THOMSEN & COMPANY, A FIRM OF NEW YORK, N. Y., COMPOSED OF G. A. FEEDERSEN, H. JOHN RIEDEL, CHARLES A. THOMSEN, AND G. C. FEEDERSEN.

TOY ANIMAL.

Application filed June 14, 1924. Serial No. 719,994.

This invention relates to toy animals and has for its object to provide such a toy in a form that will particularly appeal to children by the employment of candy, preferably in wrapped form, in the make-up of the toy.

5 The invention consists in the novel features of construction and combinations of parts as hereinafter described and claimed, 10 and as illustrated in the accompanying drawings, in which—

Figure 1 is a plan view of a blank of cardboard or like material from which the frame or body structure of the toy is made up.

15 Fig. 2 is a side view of the toy—here shown in the form of a dog—made up from the blank shown in Fig. 1 with the addition of a head member and also of wrapped candies forming part of the body and legs.

20 Fig. 3 is a rear end view of the toy dog shown in Fig. 2 located within a container in the form of an open-ended triangular shaped tent.

Fig. 4 is a side elevation of the same with 25 the container partly broken away at its front end and the dog positioned therein with its head projecting through the front end of the container.

Fig. 5 is a sectional detail taken on the 30 line 5—5 of Fig. 2, showing the pivotal connection of the head with the body.

In accordance with my invention the frame or body structure of the toy is adapted to be made of cardboard or like material 35 capable of being readily fashioned into the general form of an animal, such for instance as the dog here shown, and to which candies may be attached in position to form, or correspond with, certain members of the animal, such as the body and legs.

In carrying out my invention in a preferred form thereof, I cut a blank from cardboard or like material of the general form shown in Fig. 1, which comprises a 45 relatively wide elongated body portion 2, from which extend at opposite sides thereof a pair of fore-leg members 3—3, and a pair of hind leg members 4—4, these two pairs of leg members being adjacent the opposite 50 ends of the body portion 2. In making up the toy figure from this blank the leg members are bent to depend downwardly from the body portion as shown in Figs. 2, 3 and 4. In order to maintain the leg members

in properly spaced relation and impart to the figure a certain desirable rigidity, the blank is formed with extensions 5 of the leg members which, when the blank is set up, are adapted to overlap between each pair of legs, as shown in Fig. 3, and be secured together by a suitable fastening means, such, for instance as an adhesive, which is the means here employed.

Mounted upon the flat top of the body portion 2 is a wrapped candy 10 constituting the body proper of the animal. This candy 10 may be secured in position in any suitable or desired way. Preferably and as here shown I form the blank with a pair of holding members adjacent each end of the body portion 10 which are adapted to be turned upwardly and clamp therebetween the extended ends of the candy wrapper, the said members at the front end of the body portion, indicated at 11—11, being held in 75 clamping connection with the wrapper end 12 by a staple 13, and the members at the rear end of the body portion, indicated at 14—14, being similarly held in clamping connection with the opposite wrapper end 15 by a staple 16.

Preferably and as here shown, I also mount wrapped candies 17 on the outer side of each of the cardboard leg members, these 85 preferably being detachably secured to said leg members by passing the extended wrapper ends 18 through eyelets 19 in the cardboard into which they are conveniently inserted through connecting slits 20 cut in from the adjacent edges of the cardboard 90 blank as shown. The candies 17 being thus detachably connected to the leg members 3 and 4, permits of their being readily removed to be eaten without destroying the 95 structure of the toy in any way.

The head of the animal is also made of cardboard which is printed or otherwise marked in representation of a dog's head as shown. This head member if desired may be made of a single thickness of paperboard 100 suitably marked on opposite sides thereof, but I prefer to form the same from a blank which is adapted to be folded on itself at the nose end thereof, as at 25 in Fig. 3, to form parallel face members 26—26 and the 105 opposite ends of which are adapted to be reversely folded to provide the ear members 27—27. The head thus formed is piv

oted to the upturned members 11-11 of the body portion by means of a fastener 28 passing through openings in the connected parts as clearly shown in Fig. 5. This pivotal support of the head permits of a movement of the same relative to the body which obviously adds to the life-like appearance of the animal. As a cheap and simple means for providing the tail of the animal, the 10 wrapper end 15 is made of sufficient length for this purpose as shown.

The toy dog may be made up and handled commercially as a complete article in the form shown in Fig. 2, but as an added 15 feature I prefer to provide an open-ended container 30 for the same in the form of a so-called "pup" tent. This container is of sufficient length to completely enclose the dog and as here shown is triangular in 20 cross-section to conform to the similar cross-section of the dog and engage the latter, as shown in Fig. 3, whereby to frictionally hold it therein. This frictional engagement between the open-ended container and dog permits 25 of the latter being held wholly within the container for shipping or other purposes, or of being partially projected from its position within the container as shown in Fig. 4 for display or like purposes. When 30 the dog is positioned wholly within the container, his head will of course be lowered from the position shown in Fig. 4, but when removed or partially projected from the tent his head may be rocked about the pivot 35 28 to any desired position.

What I claim is:

1. A toy animal, comprising a piece of 40 cardboard or like material formed with a substantially horizontal body-supporting portion and legs depending from the edges thereof, a head member pivoted to the body supporting portion for movement, and a wrapped candy attached to the body supporting portion and constituting the body proper.

2. A toy animal, comprising a piece of 50 cardboard or like material formed with a substantially horizontal body-supporting portion and leg supporting portions depending therefrom, a head member pivoted to the body supporting portion for movement, and wrapped candies attached to said body and leg supporting portions at the outer sides thereof to constitute the body and legs proper.

3. A toy animal, comprising a piece of 60 cardboard or like material formed with a body portion and legs, the body portion presenting a substantially horizontal supporting surface from which a pair of legs depend adjacent the front and rear ends thereof, a wrapped candy secured on the surface of the body portion and constituting the body proper, and a head member attached 65 to the front end of said body portion.

4. A toy animal, comprising a piece of cardboard or like material formed with a body portion and legs, the body portion presenting a substantially horizontal supporting surface from which a pair of leg 70 supporting members depend adjacent the front and rear ends thereof, wrapped candies attached to said body and leg supporting members at the outer sides thereof to constitute the body and leg proper, and a head member attached to the front end of said body portion.

5. A toy animal, comprising a piece of cardboard or like material formed with a body portion and legs, the body portion presenting a flat supporting surface and having 80 a pair of upturned holding members at each end thereof, a wrapped candy resting on the said supporting surface of the body portion and having the extended ends of its 85 wrapper secured between the said holding members at the opposite ends of the body portion, and a head member attached to one end of the latter.

6. A toy animal, comprising a piece of 90 cardboard or like material formed with a body portion and legs, a wrapper candy attached to the body portion to constitute the body proper and having its wrapper extended at one end to form a tail member, 95 and a head member attached to the front end of the body portion.

7. A toy animal, comprising a piece of 100 cardboard or like material formed with a body portion and legs, the body portion presenting a flat supporting surface, a wrapped candy resting on the said supporting surface of the body portion and having its wrapper extended at one end to form a tail member, 105 and a head member attached to the front end of the body portion.

8. A toy animal, comprising a piece of 110 cardboard or like material formed with a body portion and legs, the body presenting a flat supporting surface and having a pair of 115 upturned holding members at its rear end, a wrapped candy resting on the said supporting surface and having its wrapper extended at one end to form a tail member, said tail member extending between the upturned holding members at the rear end of the body portion, fastening means securing the tail member between said upturned holding members, and a head member attached 120 to the front end of said body portion.

9. A toy animal, comprising a piece of 125 cardboard or like material formed with a body supporting portion and legs, the body portion presenting a substantially horizontal supporting surface from which a pair of legs depend adjacent the front and rear ends thereof, spacing members between each pair of legs to hold them in spaced relation, a wrapped candy secured on the substantially horizontal surface of the body portion and 130

constituting the body proper, and a head member attached to the front end of said body portion.

10. A toy animal, comprising a support having a substantially horizontal body-supporting portion and legs depending at an angle from said body-supporting portion, a wrapped candy attached to said body-supporting portion and constituting the body proper, a head member attached to one end of said body-supporting portion, and a container therefor in the form of an open-ended tent, frictionally engaging said toy animal to hold it either wholly or partially therein.
15. 11. A toy animal, comprising a piece of cardboard or like material formed with a body portion and legs with holes adjacent the ends of the legs, a head member pivoted to the body portion for movement, and wrapped candies attached to said body portion and legs at the outer sides thereof to constitute the body and legs proper, the wrappers of the candies on the legs being extended and passed through the holes therein.
20. 12. A toy animal, comprising a piece of

cardboard or like material formed with a body portion and legs, the body portion presenting a flat supporting surface from which a pair of legs depend adjacent the front and rear ends thereof, a wrapped candy secured on the flat surface of the body portion and constituting the body proper and having its wrapper extended at one end to form a tail member, and a head member attached to the front end of said body portion.

13. A toy animal, comprising a piece of cardboard or like material formed with a body portion and legs with holes adjacent the ends of the legs, the body portion presenting a flat supporting surface from which a pair of legs depend adjacent the front and rear ends thereof, wrapped candies attached to said body portion and legs at the outer sides thereof to constitute the body and legs proper the wrappers of the candies on the legs being extended and passed through the holes therein, and a head member attached to the front end of said body portion.

In testimony whereof I affix my signature.

DOROTHY R. WATERS
